Des. 191,993
Patented Dec. 26, 1961

191,993

CIGARETTE VENDING MACHINE

Frank Realmuto, Bayside, N.Y., and Jerome J. Golumbo,
Boston, Mass., assignors to Command Industries Corp.,
Boston, Mass.

Filed Jan. 12, 1961, Ser. No. 63,514

Term of patent 14 years

(Cl. D52—3)

FIG. 2

FIG. 1

FIG. 4

FIG. 1 is a front elevation of a cigarette vending machine embodying our new design.

FIG. 2 is a side view.

FIG. 3 is a rear elevation, and,

FIG. 4 is a perspective view thereof.

The undisclosed side of the cigarette vending machine is substantially the same in appearance as the side shown.

We claim:

The ornamental design for a cigarette vending machine, as shown and described.
